UNITED STATES PATENT OFFICE.

JAMES E. SEELEY, OF LOS ANGELES, CALIFORNIA, ASSIGNOR TO
SYNCHRONOUS STATIC CO., OF LOS ANGELES, CALIFORNIA, A
CORPORATION OF CALIFORNIA.

ELECTRICAL DISCHARGE APPARATUS.

No. 821,832.

Specification of Letters Patent.

Patented May 29, 1906.

Application filed January 25, 1905. Serial No. 242,598.

To all whom it may concern:

Be it known that I, JAMES E. SEELEY, a citizen of the United States, residing at Los Angeles, in the county of Los Angeles and State of California, have invented a new and useful Electrical Discharge Apparatus, of which the following is a specification.

The main object of the invention is to provide an electrical discharge apparatus which is adapted for energization by either alternating or direct current circuits.

A further object of the invention is to provide means for adjustment of the apparatus to different conditions of voltage or frequency in the circuit.

A further object is to provide in connection with a discharge apparatus an induction-coil of such character that the back induction in the primary or energizing circuit will be reduced to a minimum, thereby obviating the inconvenience and risk due to occurrence of high potentials on the exposed parts of the apparatus other than the discharge terminals.

The apparatus embodying the invention may conveniently be inclosed in a suitable box or case, and it is preferred to place the interrupter, reactance-coil, switches, and condenser in the body of the box and place the induction-coil proper in the lid or cover of the box which is hinged to the body, the discharge-terminals extending through the lid or cover, so as to be presented in exposed condition when the box is closed. The invention is particularly intended for use in connection with X-ray apparatus and the like, but may have other applications.

The accompanying drawings illustrate the invention.

Figure 1 is a plan of the box in open condition, showing the various elements of the induction apparatus more or less diagrammatically and the false bottom in the box being partly broken away. Fig. 2 is a section on the line $x^1 x^1$ in Fig. 1. Fig. 3 is a section on the line $x^2 x^2$ in Fig. 2.

1 designates the inclosing box or case, which may be provided with a cover or lid 2, hinged thereto, as at 3. The interrupter 4, its operating-magnet 5, regulating reactance-coil 6, condenser 7, main switch 8, and circuit-changing switch 9 are all preferably inclosed in the body of the box.

The induction-coil proper for transforming

the discharge from the condenser into impulses of high voltage is preferably inclosed in the lid or cover of the box, the primary coil 10 thereof being connected by flexible connections to the inducing apparatus in the box and the secondary coils 11 being connected to posts 12, which extend through the top of the lid and are provided with slideable or adjustable discharge-terminal rods 13, between which the discharge is to pass.

The interrupter 4 comprises contacts 14, 15, contact 14 being formed as an adjustable screw passing through a post 16, and the contact 15 being carried by a support 17, connected to be operated by the armature 18 of the magnet 5.

The specific form of interrupter herein shown forms the subject-matter of a separate application, Serial No. 243,631, filed February 1, 1905, and is herein shown and described only in a general way. The same comprises a ribbon 20, of an elastic material, such as steel, stretched between two supports 21* on a supporting-plate 21 and carrying a bracket 22, to which is attached the armature 18 aforesaid and also the contact-supporting member 17, which is formed as a spring-plate or leaf-spring secured at its lower end to the bracket 22 and extending at its upper end alongside the upper end of the vertical arm of bracket 22, but a little removed therefrom, so that on attraction of the armature said vertical arm will impinge against said spring-support and separate the contacts.

A depression 23 is formed in one of the supports 21* under the ribbon 20, and a lever 24, pivotally supported at 25 on the support 21, has a lug or bar 26 engaging said ribbon over said depression, the other end of said lever being engaged by a depression-screw 27, whereby the lever may be depressed more or less to cause the bar 26 to press or bend the ribbon into the depression 23, thereby increasing the tension of the ribbon and the periodicity or frequency of vibration of the ribbon and attached parts to the required extent.

The regulating self-inductive or reactance coil, which serves both for adjusting the reactance and resistance of the primary circuit, comprises a core member 30, wound with a coil 31, divided in sections, from which con-

nections lead to fixed contacts 32, over which slides a movable contact 33, which may be supported and guided on a fixed rod 34.

A false bottom or cover-plate 65 extends over the various devices 5, 6, and 7 in the box. The contact devices 32 33, switches 8 and 9, and regulating-screws 14 27 are above this plate.

The induction-coil preferably comprises two secondary coils each substantially disk-shaped, with the outer edges of the disks substantially tangential or in close proximity and the primary coil surrounding both the said disk coils and curved in or reentrant at each side to conform substantially to the contour of the secondary coils. It is found that the best results are obtained by bringing the secondary coils closely together and extending the primary coils inward as far as possible between the secondary coils.

The secondary coils are wound spirally, the inner terminal of each secondary coil being connected to the corresponding terminal post 12 and the outer terminal of one of said secondary coils being connected to the outer terminal of the primary coil, while the outer terminal of the other secondary coil is connected to the inner terminal of the primary coil.

35 36 designate binding-posts or terminals for the supply connections which may lead either direct or alternating circuit.

The switch 8 comprises two switch-arms 37 38, connected by an insulating operating-bar 39 and engaging fixed contacts 40 41 40', operating as a reversing-switch. The switch 9 comprises three switch-arms 42 43 44, coöperating with the fixed contacts 45 46 47 and mechanically connected to move in unison by insulating operating-bar 48, this switch serving to change the circuit connections for alternating a direct-current operation.

The switch-arms 37 38 are respectively connected to line-terminals or binding-posts 35 36 by wires 50 51. The wire 52 connects contacts 40 40' of switch 8 with contact 45 of switch 9, and a connection 53 leads from this wire to one end of the reactive resistance-coil 31. From the terminal rod 34 for said coil a wire 54 leads to the contact 46 of switch 9. Contact 47 of switch 9 is connected by a wire 55 to one end of the energizing-coil of magnet 5, the other end of which is connected by a wire 56 with arm 42 of switch 9. Arm 43 of switch 9 is connected by a wire 57 with one side of the condenser 7, and a connection 58 leads from the same side of the condenser to the supporting-post 16 for the fixed interrupter-contact. Arm 44 of switch 9 is connected by a wire 59 to a conductor 60* and terminal 60, from which a flexible connection 61 extends to a terminal 62 in the lid connected to one end of the primary of the induction-coil, the other end of said primary being connected to a terminal 62', from which a flexible connec-

tion 61' extends to a terminal 60', connected to the other side of the condenser. The arm 44 of switch 9 is also connected by a wire 63 to contact 41 of switch 8. The conductor 60* is connected to the metallic base 21 of the interrupter.

In using the apparatus with an alternating circuit switches 8 and 9 are placed, respectively, in lower dotted position and in full-line position. The alternating current entering at terminal 35 passes by wire 50 through switch-arm 37 to contact 40, wire 52, contact 45, switch-arm 42, wire 56, coil of magnet 5, wire 55, contact 47, switch-arm 44, wire 63, switch-arm 38, wire 51, to line-terminal 36. The current so passing alternately energizes and deenergizes said magnet, causing periodical attraction of its armature.

The regulating-screw 27 of the interrupter should be so adjusted that the natural periodicity of vibration of the torsion-spring 18 with the attached armature and contact will correspond to the periodicity of alternation of the current. Contact will thus be made and broken in a charging-circuit leading as follows: from line-terminal 35 through wire 50, switch-arm 37, wire 53, reactive or self-inductive resistance-sections 31 to one of the contacts 32, sliding contact 33, rod 34, wire 54, contact 46, switch-arm 43, wire 57, 95 to one side or terminal of the condenser, thence by wire 58 to interrupter contact-post 16, contacts 14 15, and the metallic supporting devices of the latter, to wire 59, wire 63, switch-arm 38, wire 51, and the other side of the line at 36. The impedance of this charging-circuit can be adjusted to give the requisite flow of current by shifting contact 33 to cut in more or less of the sections of coil 31. At each interruption of this charging-circuit there will be a reactive or self-inductive impulse of high potential generated by the reactive device 6, the magnitude of which can be adjusted by varying the number of sections of coil 31 included in circuit by shifting the sliding contact 33.

This impulse will charge the condenser; the current passing from line-terminal 35 through the reactive resistance 31, as above traced, and through the switch-arm 43 to one side of the condenser and from the other side of the condenser through the connections 60' 61' 62', primary coil 10, and connections 62 61 60 60* 59 63 38 51 to the other side of the line. As soon as this self-inductive impulse has reached its maximum and there is a corresponding charge of the condenser the potential in the reactive device 6 will begin to fall and the condenser will begin to discharge through the condenser-circuit in the primary coil 10. At this moment or immediately thereafter the interrupter will close the condenser discharge-circuit at the terminals 14 15, the discharge passing from the condenser through wire 58, contacts 14 15, the metallic supporting devices of the latter, connection 130

- 60^a, terminals 60, connection 61, terminal 62, primary coil 10, and connections 62' 61' 60' to the other side of the condenser. This discharge-circuit will be of extremely low resistance, as it does not include any part of the charging self-induction coil 31, and the oscillatory discharge from the condenser through this circuit will be of correspondingly high frequency.
- 10 The oscillatory discharges in the primary coil 10 will induce discharges in the secondary coils 11, thereby generating alternating impulses of extremely high frequency and potential at the discharge-terminals 13, which are connected, respectively, to the inner ends of the respective secondary coils 11. The connection on the other ends of the respective secondary coils 11 to the respective ends of the primary coil 10 has the effect of preventing the passage or back kick of high-potential discharges from the primary coil to the exposed terminals and conductors of the charging-circuit and devices.

It will be seen that in using the device with alternating current, as above described, the current is divided in two circuits in parallel relation, part of it passing through the magnet 5 in a circuit exclusive of the interrupter to operate the interrupter in synchronism with the alternating current, while the remainder of the current passes in a circuit through the coil 31 of reactive induction device 6 and through the interrupter exclusive of magnets to generate the self-inductive impulses for charging the condenser, and that the moment the condenser has become charged a short circuit is closed independent of the electromagnetic inductive devices 5 6.

In using the apparatus with direct current the switch 9 is placed in the dotted-line position, and the current will pass from line-terminal 35 through wire 50, switch-arm 37, wire 53, inductance-coils 31, contact 33, rod 34, wire 54, contact 46, switch-arm 42, wire 56, coil of magnet 5, wire 55, contact 47, switch-arm 43, wires 57 58, contacts 14 15, wires 59 63, switch-arm 38, and wire 51 to the other line-terminal 36. The switch 8 is made as a reversing-switch to provide for reverse connection, if desired. The current above traced passes through the reactive or self-inductive coils 31, coil of magnet 5, and the interrupter in series, with the result that it will be repeatedly interrupted, and at each interruption a self-induction impulse will pass from the line and reactive coil to the condenser as follows: from the line to the reactive coils 31 and coil of magnet 5, as above traced, and through wire 57 to one side of the condenser and from the other side of the condenser through the primary coil to wires 59 and 63 to the other side of the line, as above traced, for the alternating circuit. Thus the discharge from the condenser will pass through a short circuit, including the primary coil, exclusive of

the other electric magnetic inductive devices, as above explained.

The fact that the primary is made in one coil surrounding the two coils of the secondary avoids the inductance of the connections that would have to be used with two separate primaries, thereby reducing the inductance of the discharge-circuit to a minimum. The fact that the two secondary coils are side by side has the advantage over constructions where the coils are placed end to end in that the mutual induction thereof is minimized.

What I claim is—

1. In an electrical apparatus for the purpose described, a self-inductive coil, an interrupter, an operating-magnet therefor, energizing connections for direct-current operation establishing a circuit including the self-inductive coil, the interrupter-operating magnet and the interrupter, in series, energizing connections for alternating-current operation establishing a circuit including the interrupter-operating magnet exclusive of the interrupter, and a circuit including the self-inductive coil and the interrupter, exclusive of the interrupter-operating magnet, a switch for cutting in and out the alternating and direct current circuits alternatively, a condenser, an induction-coil, and a discharge-circuit including the condenser, the primary of the induction-coil and the interrupter.

2. In an electrical apparatus for the purpose described, a self-inductive coil, an interrupter, an operating-magnet therefor, energizing connections establishing a circuit including the self-inductive coil, the interrupter-operating magnet and the interrupter, in series, a circuit including the interrupter-operating magnet exclusive of the interrupter, and a circuit including the self-inductive coil and the interrupter exclusive of the interrupter-operating magnet, a switch connected to the respective circuits and operating in one position to close the first-mentioned circuit, and in another position to close the other two of said circuits in parallel relation, a condenser, an induction-coil, and a discharge-circuit including the condenser, the primary of the induction-coil and the interrupter.

3. In an electrical apparatus for the purpose described, a self-inductive coil, comprising a plurality of sections and contact devices for including a variable number of said sections in circuit, an interrupter, an operating-magnet therefor, energizing connections for direct-current operation establishing a circuit, including the self-inductive coil, the interrupter-operating magnet and the interrupter, in series, energizing connections for alternating-current operation establishing a circuit including the interrupter-operating magnet exclusive of the interrupter, and a circuit including the self-inductive coil and the interrupter, exclusive of the interrupter-operating magnet, a switch for cutting in and

out the alternating and direct current circuits alternatively, a condenser, an induction-coil, and a discharge-circuit including the condenser, the primary of the induction-coil and the interrupter.

4. An electrical apparatus comprising a condenser, charging connections therefor including an electromagnetic induction device and a vibratory interrupter, an operating-magnet for said interrupter, an energizing connection for said induction device exclusive of the interrupter for control thereof by alternating current, and a discharge-circuit including an induction-coil having its primary connected in circuit with the condenser and interrupter.

5. An electrical apparatus comprising a condenser, charging connections therefor including an electromagnetic induction device and a vibratory interrupter, means for adjusting the rate of vibration of said interrupter, an operating-magnet for said interrupter, an energizing connection for said induction device exclusive of the interrupter for control thereof by alternating current, and a discharge-circuit including an induction-coil having its primary connected in circuit with the condenser and interrupter.

6. An electrical apparatus comprising a condenser, charging connections therefor including an electromagnetic induction device and a vibratory interrupter, means for adjusting the rate of vibration of said interrupter, consisting of an elastic support, and means for adjusting the tension of said support, an operating-magnet for said interrupter, an energizing connection for said induction de-

vice exclusive of the interrupter for control thereof by alternating current, and a discharge-circuit including an induction-coil 40 having its primary connected in circuit with the condenser and interrupter.

7. In an electrical apparatus for the purpose described, an induction-coil comprising two secondary coils side by side, and a primary coil surrounding both the secondary coils.

8. In an electrical apparatus for the purpose described, an induction-coil comprising two secondary coils side by side, and a primary coil surrounding both the secondary coils and projecting inwardly between the secondary coils.

9. In an electrical apparatus for the purpose described, an induction-coil comprising 55 two secondary coils side by side, and a primary coil surrounding both the secondary coils, the outer ends of the secondary coils being connected to the ends of the primary coil, and discharge-terminals connected to 60 the inner ends of the secondary coils.

10. In an electrical apparatus for the purpose described, an induction-coil comprising two secondary coils side by side, a primary coil surrounding both the secondary coils, 65 and discharge-terminals connected to the inner ends of the secondary coils.

In testimony whereof I have hereunto set my hand, at Los Angeles, California, this 11th day of January, 1905.

JAMES E. SEELEY.
